DESIGN FOR A RAILING BAR ORNAMENT

Joseph J. Simon, New York, N. Y.

Application October 12, 1939, Serial No. 87,640

Term of patent 7 years

To all whom it may concern:

Be it known that I, Joseph J. Simon, a citizen of the United States residing at No. 144 West 86th Street, in the city, county, and State of New York, have invented a new, original, and ornamental Design for a Railing Bar Ornament, of which the following is a specification, reference being had to the accompanying drawing, forming part thereof.

Fig. 1 is a front elevational view of a railing bar ornament showing my new design; and
Fig. 2 is an edge view thereof.

I claim:

The ornamental design for a railing bar ornament, as shown.

JOSEPH J. SIMON.
